2 Claims. (Cl. 315—39.67)

This invention relates to magnetrons and has for its object to provide improved magnetrons of high efficiency, simple construction and capable of delivering high powers at very high frequencies.

According to this invention a magnetron comprises a hollow cavity resonator within which is at least one cathode and at least two anodes in such mutual relationship as to constitute a split anode magnetron system, said system being so positioned and arranged with respect to said cavity resonator that, when in operation, it excites a standing wave therein and said cavity resonator being provided with means for the withdrawal of useful power therefrom.

The means for the withdrawal of useful power may take any of a variety of forms, for example, a loop inserted in the cavity resonator or a concentric line or wave guide output circuit.

The invention is illustrated in the accompanying drawings in which Figure 1 is a schematic sectional elevation and Figure 2 is a schematic end view of one embodiment. Figs. 3 to 8 inclusive are schematic views like Fig. 2, of further embodiments.

In the form of construction shown in Figs. 1 and 2 there is provided, off-set within a cylindrical cavity resonator 1, an electrode system consisting of a rectilinear cathode 2 axially within two similar anodes 3 each shaped like a segment of a cylinder with lineally extending spaced edges. The cathode 2 is parallel to and spaced a desired distance from the axis of the cylinder 1 and the split anode magnetron system consisting of the said cathode 2 and the anodes 3 extends over the greater part of the length of the cavity. The whole arrangement is such that operation of the said split anode system as in the normal way excites an H_{011} standing wave in the cavity resonator. This is indicated conventionally in broken lines in Fig. 2. Output energy is taken off from the cavity resonator in any manner known per se such as through the coupling means shown at 33.

Fig. 3 shows a modification suitable for use where higher power outputs are required. In Fig. 3 there is a ring of similar cathode and double anode systems each as above described. As shown the cathodes 2 are all parallel to one another and to the axis of the cavity resonator 1 and are equally spaced along an imaginary ring having the cavity resonator axis as a center. Each cathode 2 located is within two anodes 3 just as in Figs. 1 and 2 with the lineal edges of the semi-cylindrical parts or members of anodes 3 spaced on opposite sides of diametrical lines through the cavity resonator 1. The cathodes and the semi-cylindrical parts or members of anodes 3 are supported in conventional manner with respect to cavity resonator 1 through wires and spacers of conventional construction.

In a preferred and simpler construction shown in Fig. 4 and suitable for use on frequencies of the order of 30,000 mc./s. or more the segmental anodes 3 of the embodiment of Fig. 2 are replaced by rods 31 running parallel

2

to the cathodes 2, each rod serving as a common anode to two adjacent split anode magnetron systems consisting of two cathodes 2 and the common anode rod 31. Thus, as shown in Fig. 4 there may be as many rods 31 as there are cathodes 2, the rods alternating with the cathodes along, and at right angles to, an imaginary ring the axis of which is constituted by the axis of the cavity 1, each rod 31 being mid-way between two cathodes 2 and each cathode being mid-way between two rods 31.

In a further modification of the arrangement of Fig. 4 shown in Fig. 5 the cathodes 2 and rod-anodes 31 are spaced at equal intervals along and at right angles to, concentric rings having the axis of the cavity resonator 1 as a center, the cathodes 2 being in one ring, for example, the outer one, and the rods 31 in the other, and the radii to the cathodes being mid-way between the radii to the rods. In these constructions, as will be obvious, the direct current to high frequency conversion takes place by the direct interaction of the H_{011} standing wave with the electrons circulating round the cathodes under the influence of the electrostatic fields between the anodes and cathodes and the applied magnetic field, not indicated, which, of course, is crossed with respect to them. The primary function of the anodes being merely to collect electrons which have lost energy, the exact orientation of the electrostatic field between each anode and cathode with respect to the high frequency field should not be of major importance so that precise electrode location in this respect should not be a requirement. The anodes may, however, have secondary effects by introducing local disturbances of the high frequency field in their immediate neighborhoods but these disturbances may be expected to have favorable influences on electron motion in the constructions described.

In a further modification shown in Fig. 6 the anodes 31 and cathodes 2 are again in separate concentric rings and equally spaced along them but each anode is on a common radius with a cathode instead of being between two of them as in Fig. 5.

In still further modifications three concentric rings of electrodes are used, an intermediate ring of equally spaced cathodes 2 being arranged mid-way between two other rings of equally spaced anode rods 31, the said anode rods being either midway between the radii on which the cathodes lie as shown in Fig. 7 or on the same radii, not illustrated.

The multiple rod anode embodiments above described and illustrated may be modified as typified in Fig. 8 by replacing each adjacent pair of anode rods situated on the same circle by a segmental anode 32 lying on the said circle, opposite ends of each segment being, in operation, at potentials of opposite simultaneous sign and adjacent ends of adjacent segments being also at potentials of opposite simultaneous sign. This is conventionally indicated in Fig. 8 by plus and minus signs against a few of the anodes. In the construction of this nature shown in Fig. 8 there is a ring of segmental anodes 32 lying in a circle having the axis of the cavity resonator 1 as a center, there being one cathode 2 to each anode segment, the cathodes being arranged in and at right angles to a second, larger, concentric circle and each cathode being opposite the middle of an anode segment. This type of arrangement may be regarded as operating in a mode corresponding to the zero mode of a conventional multi-cavity magnetron, the electrons moving from one anode-cathode region to the next in approximately one oscillation of the cavity resonator. This is conventionally indicated in broken lines at the top of Figure 8.

The cathodes and anodes employed in embodiments of this invention may be supported in any convenient way by means which, for reasons of simplification, are not

shown in the drawings, for example the anodes may be directly attached to the ends of the cavity 1 and the cathodes may be attached by means of extensions passing through holes in the ends of the cavity resonator to external supporting structures. Necessary cathode insulation, means for providing hermetic sealing and output circuit means for taking off the generating high frequency power are, of course, provided in any convenient manner and are again not shown.

A split anode magnetron system as disclosed herein is broadly any magnetron in which the anodes are made up of two parts which may be two rod-like members as well as two segmental members.

While I have described my invention in certain preferred embodiments, I realize that modifications may be made, and I desire that it be understood that no limitations upon my invention are intended other than may be imposed by the scope of the appended claims. 15

I claim:

1. A magnetron comprising a hollow cavity resonator, 20 means for exciting a standing wave in said cavity resonator, said means comprising a plurality of split anode magnetron systems eccentrically mounted within said cavity resonator, each of said systems including a cathode

and two anode segments, said segments consisting of semi-cylindrical members spaced at their opposite lineal edges along diametrical lines through said cavity resonator and means for effecting the withdrawal of useful power from 5 said cavity resonator.

2. A magnetron as set forth in claim 1 wherein said hollow cavity resonator is cylindrical in shape and wherein said plurality of split anode magnetron systems are equally spaced along an imaginary ring within said cavity resonator and have the cavity resonator axis as a center, the cathodes of said split anode magnetron systems extending parallel to and spaced from the cavity resonator axis, and wherein each of said pairs of anode segments have the associated cathode located at their common axis. 10
